UNITED STATES PATENT OFFICE.

JOSEF BRUNO ZURA, OF BERLIN, GERMANY.

MECHANISM FOR ADMITTING OR SHUTTING OFF STEAM FOR ROTARY MOTORS.

SPECIFICATION forming part of Letters Patent No. 691,041, dated January 14, 1902.

Application filed June 30, 1898. Serial No. 684,901. (No model.)

To all whom it may concern:

Be it known that I, JOSEF BRUNO ZURA, a subject of the King of Prussia, German Emperor, residing at the city of Berlin, Germany, have invented a new and useful Mechanism for Admitting or Shutting Off Steam for Rotary Engines, of which the following is a specification.

My invention relates to mechanism for admitting steam to and shutting off steam from the cylinders of rotary motors, the slide-valve being quickly completely opened or closed and retained in either of these positions a longer or a shorter time, according to the yield of work required of the motor, so that steam is always supplied to the motor unthrottled. Further, means are provided for suddenly and completely closing the slide-valve when the load is suddenly taken off the motor.

The mechanism of the invention comprises a cam which by the extension or contraction of its periphery for the time being determines the time of full steam admission and complete cut-off, the contraction and expansion, or closing and opening, of said cam being effected through the lever mechanism of the slide-valve and retained a longer or shorter time in either position.

In the accompanying drawings, Figure 1 is a cross-section of a rotary motor with the invention applied thereto; Fig. 2, a vertical section on line $x-x$ of Fig. 1, parts similar to those shown on the left-hand side being left out on the right-hand side; Figs. 3 and 4, respectively, a front view and a sectional view of the governor and parts in connection therewith on the main shaft, the section being approximately on line $y-y$ of Fig. 3. Fig. 5 is a view of the slide-valve lever mechanism. Figs. 6 to 9 are details of the expanding and contracting cam above referred to. Figs. 10 to 12 are views of the parts employed for suddenly closing the slide-valve. Figs. 13 and 14 show cam mechanism for actuating the alternator, but not forming part of the invention. Fig. 15 shows the elements severally illustrated in Figs. 6 to 11 as assembled and in the position in which the cam l holds the roller i high and the cam n does not come into action. Fig. 16 shows the same elements also as assembled, but in

the position in which the cam n comes into action.

a is the slide-valve for opening and closing the steam-admission port; b , the steam-chest in communication with the interior of the steam-cylinder by passage c ; d , a lever fixed on the same spindle e as the slide a . Jointed to the lever d is a rod F , constructed in two parts f' f^2 , jointed together.

g is an eye-bearing provided on the motor-frame for carrying the lever h , jointed to the part f^2 of the rod F and carrying at one end a roller i and at the other end acted against by the spring k .

l is a cam fixed on the main shaft and serving to regulate the steam admission; l' , a guide-slot in the cam l , in which slot the lengthening part l^2 engages with its curved lug l^3 ; m , a link connecting the joint of the parts f' f^2 with the lever m' m^2 , carried on the motor-frame; m^3 , a lug on the lever m' m^2 , against which the cam n , Figs. 4, 11, and 12, acts when this latter is displaced by the governor; n' , a pivot on the cam n for engaging in the slot n^2 of the disk o , Figs. 4 and 12. In the cam n are curved slots n^3 , Fig. 11, in which engage the pivots n^4 , Figs. 6 and 7, of the cam l .

The steam admission and cut-off is performed by the slide a , Fig. 1, within the steam-chest h , said slide being for this purpose moved to and fro from the rod F , which through the lever d turns the slide-rod e as soon as the lever h , jointed to the rod F , is moved by the cam l when this comes in contact with the roller i , the movement of the lever h corresponding to the form of the cam l and the lever is maintained in the position corresponding to the full-open or completely-closed steam-port c so long as the roller i glides on the uniform peripheral surface of the cam l . Therefore the time during which the steam-port c is open or closed may be increased or diminished by lengthening or shortening the uniform or circular surface of the cam l , which is done by displacing the part l^2 along the slot l' . This displacement of the part l^2 may be operated by the governor P . For this purpose there is keyed on the main shaft a disk p , Figs. 3 and 4, which sets in rotation the governor-weights p' , fixed on the outer ends of the levers p^2 , mounted to turn on the pivots p^3 , fixed in the disk p . The op-

posite ends of said levers are connected by links q with a sleeve o' , carried loose on the main shaft. This sleeve rotates with the disk o ; but it can also turn in the direction of the 5 rotary movement separated from the disk o , and this occurs when the levers and weights of the governor P are moving or in action. When the weights p' are thrown outward by the centrifugal force, the levers p^2 turn on the 10 pivots p^3 , and thereby communicate, through the links q , an opposite turning movement to the sleeve o' , so that this latter and the disk p then move in contrary directions. On the sleeve o' is keyed the disk o , to which the cam 15 part l^2 is attached by screws, said cam part being guided by a projection l^3 thereon in the slot l' of the cam l . When the disk o is displaced in a direction contrary to the direction of movement of the main shaft, the cam 20 part l^2 is also displaced in the slot of the cam l and the cam thereby lengthened. The weights p' and levers p^2 are held in equilibrium by springs p^4 . The roller i , Figs. 15 and 16, runs on the periphery in the cam l 25 and holds the lever d , and with this the opening in the slide-valve for the admission of steam, so long in the same position as the roller i continues to bear upon the larger concentric part of the cam l . When the roller i 30 comes to that part of the periphery of the cam l at which it runs downward to the smaller part of the same, the position of the lever d and that of the steam-admission opening in the slide-valve changes and is held in this changed position so long as the roller i 35 runs upon the smaller concentric part of the cam l . If now by sliding the lengthening part l^2 in the guide-slot l' of the cam l the periphery of the latter is altered, so also is the 40 duration of the steam admission.

The above-described cam n , Figs. 4, 11, and 12, serves to completely close the steam-port. When the sleeve o' is displaced by the governor P against the cam l , the cam n at a certain point of the displacement passes, by reason of the oblique slots n^3 , Fig. 11, engaged by pivots n^4 , Figs. 6 and 7, upward out of the path. By this movement of the cam n the lever m' m^2 is moved as the cam n strikes 45 against the lug m^3 and presses it backward. In this movement of the lever m' m^2 the rod F is pulled open at the joint of its two parts f' f^2 , and the steam-slide thereby moved to 50 close the steam-port c .

55 Having now particularly described and as-

certained the nature of my said invention and in what manner the same is to be performed, I declare that what I claim is—

1. In rotary motors a mechanism for governing the admission of unthrottled steam 60 into the steam-cylinder, consisting in the combination of a lever h which is in connection with the slide-valve a through rod F and lever d , with the cam l composed of two concentric circular curves of different radius on 65 which the cam part l^2 is radially displaceable, and with a governor which is connected with the cam part l^2 for the purpose of varying the duration of the admission of the unthrottled steam into the steam-cylinder, said cam part 70 l^2 being connected with the part operated by the governor, substantially as described and shown.

2. In rotary motors, a mechanism for governing the admission of unthrottled steam 75 into the steam-cylinder, consisting in the combination of a lever h which is in connection with the slide-valve a through rod F and lever d , with the lever m' , m^2 , connected with the rod F through the link m , and with a 80 mechanism for drawing open the rod F at the joint of its two parts f' , f^2 , consisting of the disk o connected with the governor and of the cam n in movable connection with said disk o , substantially as described and shown. 85

3. In rotary motors, a mechanism for governing the admission of unthrottled steam into the steam-cylinder, consisting in the combination of a lever h which is in connection with the slide-valve a through rod F and lever d , with the cam l on which the cam part 90 l^2 is radially displaceable for the purpose of varying the duration of the admission of the unthrottled steam into the steam-cylinder, and with a governor connected with the cam 95 part l^2 said governor consisting of a disk p on which are eccentrically carried the levers p^2 carrying the weights p' and of a sleeve o' carried on the same shaft as the disk p and in jointed connection through links q with the 100 levers p^2 , substantially as described and shown.

In testimony that I claim the foregoing as my invention I have signed my name in presence of two subscribing witnesses.

JOSEF BRUNO ZURA.
